UNITED STATES PATENT OFFICE

163,136

POCKET ADDING APPARATUS UNIT

Kenneth R. Pangburn, Duluth, Minn.

Application May 1, 1950, Serial No. 9,608

Term of patent 14 years

(Cl. D64—11)

To all whom it may concern:

Be it known that I, Kenneth R. Pangburn, a citizen of the United States of America, residing at Duluth, in the county of St. Louis and State of Minnesota, have invented a new, original, and ornamental Design for a Pocket Adding Apparatus Unit, of which the following is a specification, reference being had to the accompanying drawing, forming a part thereof:

In the drawing:

Fig. 1 is a perspective view of a pocket adding apparatus unit with the cover opened, showing my new design.

Fig. 2 is a side perspective view of the same in a closed condition, the opposite side presenting substantially the same appearance as the side shown.

I claim:

The ornamental design for a pocket adding apparatus unit, as shown and described.

KENNETH R. PANGBURN.
